E Thomas Green

UNITED STATES PATENT OFFICE.

E. T. GREEN, OF STONEHAM, MASSACHUSETTS.

IMPROVED LAST.

Specification forming part of Letters Patent No. **59,209**, dated October 30, 1866; antedated October 20, 1866.

To all whom it may concern:

Be it known that I, E. THOMAS GREEN, of Stoneham, county of Middlesex, State of Massachusetts, have invented an Improved Last; and I do hereby declare that the following is a full and exact description thereof, reference being had to the accompanying drawings, and to the letters of reference marked thereon.

The nature of my invention consists in making a last with a movable bottom, constructed in such a manner that when the said movable bottom shall have become worn out and rendered useless the same may be taken off and a new one substituted in its place, thus saving the expense of an entire new last.

To enable others skilled in the art to make and use my invention, I will proceed to describe its construction and use.

Figure 1 is a photographic view of the last complete. Fig. 2 is a photographic view of the last as it appears without the movable part. Figs. 3, 4, and 5 represent, severally, the three parts of the last as they appear when separated.

The part F, Figs. 1, 2, and 3, is made in the same manner as a common last, but differing in form, as seen by the representation. The bottom is made perfectly flat to receive the part E. (Shown in Figs. 1, 2, and 4.)

The part E is made of any suitable metal in general form, as shown, but, of course, to vary with the style of the last, containing a socket, C, (shown in Figs. 1 and 2,) and a socket, I I'. (Shown in Figs. 2 and 4.) The object of the socket C is to admit of nailing on the inner sole while the shoe is in process of construction. The object of the socket I I' is to receive the movable bottom D. (Shown in Figs. 1 and 5.)

The part D (shown in Figs. 1 and 5) is made of wood, leather, rubber, or any other suitable material or materials, and fits the socket I I', Figs. 2 and 4, filling it and completing the last.

The several parts D, E, and F are made fast to each other by screws or nails.

The uses of the several parts of my improved last are these: The part F, Figs. 1, 2, and 3, forms the body of the last. The part E, Figs. 1, 2, and 4, completes the outline of the last, and forms a permanent part of the same. It also confines, with the aid of nails or screws, the movable part D, Figs. 1 and 5, in its proper position. The part D, Figs. 1 and 5, forms the movable bottom, to be taken out when it has become much dilapidated by use.

The advantage claimed for my improved last is that of economy, as it is well known that the bottom of a last is the only part that becomes unfit for use, and its renewal instead of the renewal of the whole last is a great saving of expense.

I am aware that S. S. Turner obtained a patent for an improved last in the year 1858; but my invention is wholly distinct from the devices described and claimed in his said patent.

My invention consists in the use of a metallic pan or basin, or its equivalent, corresponding in shape to the bottom of a last, and fitted to receive and hold a false or movable bottom, and to permit its being replaced when the same is worn out or unfit for use.

What I claim as my invention, and desire to secure by Letters Patent, is—

A metallic pan or basin, E, or its equivalent, constructed and arranged for holding a false or movable bottom of a shoe-last, in the manner and for the purposes substantially as herein set forth.

E. T. GREEN.
